B. ROSENBERG

DISPLAY RECEPTACLE

Filed Feb. 25, 1922

Benjamin Rosenberg
INVENTOR

BY

Otto Munk
his ATTORNEY.

UNITED STATES PATENT OFFICE.

BENJAMIN ROSENBERG, OF BROOKLYN, NEW YORK.

DISPLAY RECEPTACLE.

Application filed February 25, 1922. Serial No. 539,127.

To all whom it may concern:

Be it known that I, BENJAMIN ROSENBERG, a citizen of the United States, residing at Brooklyn, in the county of Kings and State 5 of New York, have invented certain new and useful Improvements in Display Receptacles, of which the following is a specification.

My invention relates to improvements in receptacles, of cardboard or analogous material, of the type in which the cover may 10 be moved into position to cover the contents of the box or into position to hold the box elevated so as to advantageously display the contents.

15 It is not new, broadly, to use the cover as a support for the box body when the latter is held in inclined or display position, but I believe that it is novel to provide the cover with particularly designed side walls 20 which project beyond the plane of the edges of the box body and embrace opposite sides of the latter for the purpose of preventing possible relative lateral movement of either cover or body portions with respect to each 25 other when the receptacle is in closed or open position.

It is the principal object of the invention 30 to provide such a receptacle comprising a single blank which shall be cut and scored and capable of being folded to form a body portion and a cover therefor; the body having its side walls folded upon themselves to provide open under edges and an end projection integral with the cover; the latter 35 being provided with side walls which extend to a point short of the free end of the cover and which embrace the folded side walls of the box body when the cover is moved to closed position and project into 40 the space between the open edges of the latter side walls when the box is supported in inclined display position; the effect of such a construction being directed towards preventing sidewise movement of the supporting 45 cover relative to the body itself.

The preferred embodiment of the invention is illustratively exemplified in the accompanying drawing, wherein

50 Fig. 1 is a view of the development of the cardboard blank, cut and scored and prior to being folded to form a receptacle.

Figs. 2 and 3 are perspective views of the folded box in closed and display positions.

Figs. 4 and 5 are substantially longitudinal sectional views of the receptacle showing 55 the cover in closed and supporting positions.

Referring particularly to Fig. 1 the blank of cardboard is cut and creased to form a bottom section 10, two side wall sections 11 and 12, end wall sections 13 and 14 and a 60 cover section 15 extending from the section 13 and having an end flap 16. The opposite end wall 14 has an integral flap 17 which is creased at 18 between itself and the wall 14 to permit a movable connection between the 65 two sections.

Each of the side wall sections 11 and 12, has a longitudinal crease 19 which divides the section into two portions *a* and *b*, the latter being disposed on the outside is provided with slit tongues 20 projecting from opposite ends thereof and beyond the ends of the portion *a*. In order to engage the slit tongues carried by side wall sections 11 and 12 with each other, it will be noted that it 70 is the left edge, of each tongue, which is slit. The tongues themselves are divided from the portions *b* by creases 21 extending transversely thereof.

The cover section 15 comprises a top section 22 having the portion adjacent the body of the blank provided with parallel transverse creases 23 by means of which the remaining portion of the cover may be folded above or beneath the box. The outermost 80 one of the creases 23 extends to a point short of the edges of the section 22 and from the ends of the crease the cardboard is cut through to the edges. At the inner ends of these cuts a pair of converging cuts 24 project toward the central portion of the cover section and to a transverse crease 25 extending between the inner ends of the cuts 24. The blank portion forming the cover section 15 is substantially the same width as 85 that of the bottom section 10 until it reaches a point slightly beyond the crease 25 where the blank widens to form right angle corners 26. The general parallel sides of the cover 15 before reaching the corners 26, are projected toward the end of the cover and beyond the corners by creases 27 by means of 90 100

which the corners 26 and extending portions 28 may be movably connected to the main top section 22 to form the sides of the cover. Adjacent the end of the wide portion of the cover section 15 the latter is provided with a transverse crease 29 and from the point where the creases 27 and 29 meet the blank is cut through to the outer end thereof to form the flap 16. The portions of the sides 28 extending beyond the crease 29 form tongues 30 having a slit 31 cut into their right edges.

The blanks may be handled in the flat until ready to be folded into box form, an 15 operation carried out in the following manner:

First, the side wall sections 11 and 12 are turned to upright position and then folded along the creases 19 to bring the outer portions *b* against the inner portions *a* on the outside of the box. The end sections 13 and 14 are raised to upright positions and the two pairs of tongues 20 interengaged outside of the end sections by overlapping 20 the portions of the tongues beyond the slits. The flap 17 is then folded towards the interior of the box along the crease 18, to a position level with the top of the side walls 11 and 12 or at an incline, as shown in Figures 3 and 5. The sides 28 and flap 16 of the cover section 15 are then turned to upright positions along the creases 27 and 29 and the tongues 30 interengaged over the flap 16. The top section 22 is turned on 30 the crease 25 so that when the cover is moved into position to cover the box the portion of material between the two slits or cuts 24 will fold under the top 22 and lie parallel with the upper edge of the side walls 11 and 12 and beneath the top section 22, as shown in Figure 4. In this position it will be noted that the sides of the cover 15 embrace the outside of the side walls 11 and 12 of the box body.

When the receptacle is to be opened and supported in display position, as shown in Figures 3 and 5, the cover 15 is swung about the creases 23 until the portion of the top 22 adjacent the end of the body lies against 50 the outer side of the overlapping tongues 20 and the cut in portion between the two converging cuts 24 is turned beneath the bottom 10 of the box. This portion between the two cuts 24 will remain on a plane level 55 with the top section 22, a plane which it will be assumed is horizontal. The closed end of the cover section 15 will receive the bottom 10 of the box and support the latter in an inclined position. In order that 60 cover section 15 and the box section may be prevented from moving sidewise with respect to each other the corner projections 26 of the sides 28 are projected into the space between the portions *a* and *b* of the side walls 11 and 12, as illustrated in Fig-

ure 3. These corners 26 may be permitted to embrace the outer face of the walls 11 and 12 when the box is supported in display position, but it has been found that by providing the walls on each side of the 70 single ply side walls 28, the supporting strength of the latter walls is greatly increased.

Having now described my invention, I 75 claim:

1. A receptacle comprising a body having lateral extensions capable of being folded longitudinally thereof to form side walls, the latter being collapsed upon themselves and capable of being united at their ends, 80 and a cover hinged midway of its length and being movably and integrally connected to one end of said body and provided with lateral extensions capable of being folded with respect to the cover and 85 united at their ends, said extensions projecting to a point short of the length of said cover and capable of embracing the opposite side walls of the body when the cover is moved into position to cover the 90 body of the box or into position beneath the body to elevate the latter.

2. A receptacle comprising a body, a cover and a connecting member movably connecting the cover to one end of said body, 95 said connecting member having transverse cuts extending inwardly from opposite edges and a pair of converging cuts extending from the inner ends of the transverse cuts to a transverse crease in the body 100 of the cover, whereby the cover may be moved into position to cover the box and the connecting member folded beneath the cover along the said transverse crease or moved into position to hold the body elevated and the connecting member folded 105 over the end of the box and along a crease between the transverse cuts.

3. A receptacle comprising a body and a cover hinged midway of its length and movably connected to one end thereof, said body being provided with side walls folded upon themselves to form pockets along the lower edges of the body, said cover being provided with upstanding end and side walls, 110 the side walls being capable of movement into said pockets when the cover is moved into position beneath the body and being further adapted to embrace the sides of the body when the cover is moved into position 115 above the body to cover the latter, said end wall being capable of moving into position to support the body in an inclined display position when the cover is folded beneath the said body.

4. A receptacle comprising a blank having a bottom section provided with sides and ends, said sides being creased longitudinally thereof and a cover section having a scored line by which the cover is movably 120

joined to one of the bottom ends, the said cover being provided with a top section having lateral projections extending longitudinally thereof and to a point short of the scored line, said projections having slit tongues at their outer ends, the cover being creased along a line parallel to the said scored line and terminated at opposite ends

in cuts extending outwardly to the edges of the blank and a pair of cuts extending from the inner ends of the first cuts into the mid-portion of the top section and joined at their ends by a transverse crease.

In testimony whereof I affix my signature.

BENJAMIN ROSENBERG.
